(57) **CLAIM**

We claim the ornamental design for an articulated debris blower, as shown.

DESCRIPTION

FIG. 1 is a left side, front perspective view of an articulated debris blower showing the new design;

FIG. 2 is a left side view thereof;

FIG. 3 is a left side, rear perspective thereof;

FIG. 4 is a right side, rear perspective thereof;

FIG. 5 is a right side view thereof;

FIG. 6 is a right side, front perspective view thereof;

FIG. 7 is a front view thereof;

FIG. 8 is a rear view thereof; and,

FIG. 9 is a right side, perspective view showing pivoted articulation of the debris blower and articulation of the debris blower nozzle.

The ornamental design which is claimed is shown in solid lines in the drawings.

Any broken lines in the drawings are for illustrative purposes only and form no part of the claimed design.
